United States Patent Office

Des. 188,199

Patented June 14, 1960

188,199

TABLE

Ernest L. Swarts and Orville B. Solie, Rockford, Ill., assignors to The Lane Company, Inc., Altavista, Va., a corporation of Virginia

Filed June 24, 1959, Ser. No. 56,526

Term of patent 14 years

(Cl. D33—14)

The figure is a perspective view of a table showing our design.

The dominant features of the design reside in those portions shown in full lines on the drawing.

We claim:

The ornamental design for a table, as shown and described.
